CLAIM

The ornamental design for a display screen with graphical user interface for an operation menu, as shown and described.

DESCRIPTION

FIG. 1 is a front view of display screen with graphical user interface for an operation menu showing my new design; and,

FIG. 2 is a perspective view, showing the design of FIG. 1 within an environment.

The outer broken line rectangle in FIG. 1 illustrates the display screen and forms no part of the claimed design. All other broken lines show environment that forms no part of the claimed design.
